UNITED STATES PATENT OFFICE.

HERMAN MACK, OF HAMM, GERMANY.

ART OF EXTRACTING COAL IN MINES.

1,422,874.

Specification of Letters Patent. Patented July 18, 1922.

Application filed October 3, 1917. Serial No. 194,519.

(GRANTED UNDER THE PROVISIONS OF THE ACT OF MARCH 3, 1921, 41 STAT. L, 1313.)

To all whom it may concern:

Be it known that I, HERMAN MACK, a citizen of Germany, residing at Borbergstrasse, 3, Hamm, Westphalia, Germany, have invented certain new and useful Improvements in the Art of Extracting Coal in Mines (for which I have filed applications in Germany Sept. 8, 1916, Nov. 29, 1916, and Jan. 13, 1917), of which the following is a specification.

My invention relates to extracting coal and has for its object to provide a process for extracting coal by means of a compressed gaseous fluid such as air.

Hitherto, it has been proposed to soak a bed of coal with water and to burst the coal off by means of water under pressure. Although this process obviates the production of dust, however, the process is not efficient 20 considered generally, and has not been applied to any extent. If, instead of water under pressure, a highly compressed gaseous fluid such as air is introduced into the bore hole, a better effect is obtained as regards 25 the separation of the coal, however, this method is accompanied by a troublesome and dangerous development of very great volumes of dust.

According to my present invention I provide for a successful and dangerless extraction of coal by employing a moistened compressed gaseous fluid such as air as a blasting agent. To obtain, for instance, compressed air in a moistened state, the compressed air may be cooled down whereby the steam or vapor contained in the compressed air is condensed, the condensing resulting 35 in a moistening of the compressed air prior to its introduction into the bore hole. To obtain the same effect steam or a liquid may 40 be added to any compressed gaseous fluid while passing to the bore hole.

I have found that it is especially useful to introduce a suitable liquid, as, for instance, water, or oil, or the like, into the bore hole first and thereafter the highly compressed gaseous fluid. As a result of this procedure the water penetrates into all the fissures and crevices of the coal bed in a similar manner as with the coal bed soaking 50 method, and acts then as a tightening substance for the compressed gaseous fluid.

Under such condition the effect of the forcing and expanding compressed air within the coal bed is especially great and any development of dust is suppressed in the beginning.

To render my invention more clear I have illustrated, in a diagrammatical manner and by way of example, some useful devices for the application of my novel process in the accompanying drawings, in which Figure 1 shows a water introducing device arranged within a compressed air admission pipe. Figure 2 illustrates the manner of tightening the compressed air admission pipe within the bore hole previously charged with water. Figure 3 shows a movable device for the practical application of my novel process.

In order to saturate the compressed air 70 with moisture on its way to the bore hole, the admission pipe for the compressed air may be provided with a water introducing device acting in the manner of an injector. Such a device is shown in Figure 1 by way 75 of example. Compressed air is passing through the pipe *a* in the direction of the arrows. A water container *b* is connected to the pipe *a* by means of the pipes *c* and *d*. The relation of these parts is such that the 80 liquid is drawn from the container *b* by suction or injector action. While the water issues from the end of the pipe *c* it is mixed with the compressed air, is delivered to the flexible pipe *g* enters the bore hole and penetrates into the bed of coal.

If it is desired to charge the bore hole with water first, it is essential to provide for a good tightening of the compressed air admission pipe within the bore hole. For 90 that purpose I prefer to use a device such as I have shown by way of example in Figure 2. The end of the compressed air admission pipe *e* is provided with a fixed collar *h*. Rings or disks *f* of a rigid material are passed over the pipe *e* and alternate with rings or disks *g* of a yielding material. These disks *f* and *g* can be compressed in an axial direction between the collar *h* and a screw threaded nut *i* by turning 95 the latter. The yielding disks *g* are enlarged circumferentially under the compressing force exerted by means of the nut *i* and come in close contact with the walls of the 100

bore hole. Between each two adjacent disks *g* are thus produced chamber like spaces which provide for a favorable acting tightening on the labyrinth principle. A good 5 tightening effect is obtained in this manner in spite of the fact that the walls of the bore hole will never be smooth, and crevices will always extend from the bore hole into the coal mass.

- 10 To enable one to extract coal in accordance with this novel process at any place no matter whether there are any pipe lines, a movable device, such as is shown in Figure 3, may be employed. A compressed gas 15 container *l* and a closed water vessel *m* are mounted upon a movable car *k* and are interconnected by means of a pipe *n* provided with a shutting-off device *o*. Another pipe *p* dips into the water contained in the vessel *m* and connects with a flexible pipe *q* which leads to the bore hole. When the valve *o* is opened, the compressed air enters the vessel *m* and presses the water contained therein through the pipes *p* and *q* into the bore hole. To allow the water sufficient 20 time to be gradually distributed into the various fissures of the coal bed, it is advisable to open the valve *o* but partly at first. When thereafter the valve *o* is further 25 opened the compressed air enters into the bore hole and the coal bed and produces a blasting off of the coal. Instead of one water vessel a plurality of such may be used in conjunction with one or a plurality of 30 compressed air containers mounted upon the car *k*.

The above described process of extracting coal is in no way inferior in its effect to any blasting by means of explosives, but has the 35 great advantage of being applicable with perfect safety in choke-damp-mines.

What I claim as my invention and desire to secure by Letters Patent of the United States is:—

1. A process of extracting coal, consisting in introducing a moistened compressed gaseous fluid into a bore hole of the coal bed. 45
2. A process of extracting coal, consisting in introducing a moistened compressed gaseous fluid of high tension into a bore hole of the coal bed. 50
3. A process of extracting coal, consisting in charging a bore hole of the coal bed with a compressed gaseous fluid and mixing the 55 said compressed fluid with a moistening agent prior to the introduction of said compressed fluid into the bore hole.
4. A process of extracting coal, consisting in charging a bore hole of the coal bed with 60 a compressed gaseous fluid of high tension and mixing the said compressed fluid with a moistening agent prior to the introduction of said compressed fluid into the bore hole.
5. A process of extracting coal, consisting in charging a bore hole of the coal bed with a compressed gaseous fluid and previously charging said compressed fluid with a gaseous moistening agent. 65
6. A process of extracting coal, consisting in charging a bore hole of the coal bed with a compressed gaseous fluid of high tension and previously charging said compressed fluid with water vapor. 70

In testimony that I claim the foregoing as 75 my invention I have signed my name in presence of two subscribing witnesses.

HERMAN MACK.
